ELECTRICALLY CONTROLLED SWITCH

Osborne I. Price, Frederick, Md., assignor to Magnetic Devices, Inc., Frederick, Md., a corporation of Maryland

Original application September 14, 1942, Serial No. 458,263. Divided and this application February 22, 1944, Serial No. 523,461

4 Claims. (Cl. 174—140)

1

My invention relates broadly to switches for high potential, high frequency electrical circuits and more particularly to a construction of a quick acting electric switch of high insulation properties operative to establish selective connection between high frequency circuits with high electrical efficiency.

This application is a division of my abandoned application Serial No. 458,263 filed September 14, 1942, for electrically controlled switch.

One of the objects of my invention is to provide a construction of electrical switch for high potential, high frequency operation with parts arranged for maximum electrical efficiency and minimum corona.

Another object of my invention is to provide a simplified construction of high frequency, high potential electrical switch having rapid acting solenoid control means associated therewith for shifting the angular position of a contact arm for controlling the transfer of one electrical circuit to another with minimum electrical losses.

Still another object of my invention is to provide an improved construction of contact mounting for a high frequency electrical switch for insulating the high frequency electrical circuits associated with the contact mounting and substantially preventing discharge to ground.

Other and further objects of my invention reside in the construction of electrical switch set forth more fully in the specification hereinafter following by reference to the accompanying drawings in which

Figure 1 is a plan view of the high frequency electrical switch of my invention; Fig. 2 is a side elevational view of the electrical switch with portions of two of the contact mountings broken away and illustrated in cross section.

Referring to the drawings in detail, reference character 1 designates the metallic base support for the electrical switch on which there is mounted a solenoid casing 2 adjacent one end and a multiplicity of pedestal insulators shown at 3, 4, 5 and 6 adjacent the opposite ends. The solenoid casing 2 is cylindrical in shape and is formed from magnetic material to provide a return path for the magnetic lines of force through the solenoid. The solenoid casing is solidly secured to the base 1 in a manner in which the solenoid is not dislodged by shock vibration during rapid action of the electric switch.

Insulated flexible wire connections 30a and 30b from the solenoid operating winding extend through apertures in the end of solenoid casing 2 to terminals 31 carried by terminal block 32.

2

of insulation material. Terminal block 32 is secured to casing 2 by means of screw threaded studs 33 and 34 which project upwardly from casing 2 through apertures in terminal block 32 and are engaged by nuts 35 and 36 which secure the terminal block 32 in fixed relation to the solenoid casing 2. Convenient connection is made to binding posts 31 for connecting the solenoid winding in the control circuit. The end of the reciprocating core member 29 is flattened as represented at 37 and is apertured at 38 for the passage of a pin 39 which pivotally connects the end of the two links 40 and 41 of insulation material. The links 40 and 41 extend on opposite sides of the arm 42 which is also formed from insulation material and pivotally connect with the arm 42 by means of pin 43 preferably formed from insulation material. The arm 42 is journaled in the standards 45 and 46 of insulation material by means of pin 44 of insulation material. The standards 45 and 46 are secured to base member 1 by means of screws 48 which pass through supporting base 1. The standards 45 and 46 are spaced sufficiently to allow the links 40 and 41 which extend on opposite sides of the insulated arm 42 to pass freely between the standards and beneath the journal formed by pin 44 in effecting angular movement of arm 42.

The end of arm 42 carries a capping member 49 secured thereon by suitable means. The capping member 49 serves as a carrier for bracket members 51 and 52 which are suitably secured to the capping member 49. The bracket members 51 and 52 serve as securing means for the cross-arm 53 of conductive material. A rivet passes through recesses in bracket members 51 and 52 and through cross-arm 53 for maintaining arm 53 in position. The recesses in bracket members 51 and 52 provide convex surfaces over which arm 53 is adapted to slightly rock in adjusting its position to make good electrical connection between the contactors carried by the arm and the coacting aligned fixed contacts. The conductive cross-arm 53 has sets of disc-like contacts mounted at opposite ends thereof and on opposite sides thereof as shown at 54 and 55 at one end and at 56 and 57 at the opposite end. These contacts coact with sets of fixed contacts mounted in insulated relation to the supporting base 1.

To provide for the insulated mounting of the fixed contacts, I arrange screw threaded studs represented at 58, 59, 60 and 61 which enter screw-threaded recesses in the upper ends of the pedestal insulators 6, 5, 3, and 4, respectively. In order to provide for adequate insulation and

prevent leakage of high frequency energy the lower extremities of each of the screw-threaded recesses which receive the screw-threaded studs are each packed with a paste-like electrically conducting material represented at 62 in Fig. 2, having a relatively high graphite content. Similarly the securing means by which the pedestal insulators are attached to the base enter screw-threaded recesses in the pedestal insulators as represented for example at 63 in Fig. 2 which are packed with paste-like electrically conducting material such as graphite as represented at 64. The intimate association of the metallic parts with the insulated material decreases the tendency of brush or corona discharge under conditions of high potential operation of the switch.

The pedestal insulators 6 and 5 have the studs 58 and 59 projecting axially therefrom through washer members 65 and 66. Pedestal insulators 3 and 4 each have similar arrangements indicated by washer members 69 and 70. The studs 58 and 59 each pass through apertures adjacent opposite ends of strip member 71 which electrically connects the terminals carried by pedestal insulators 6 and 5. Bracket member 72 is mounted on stud 58 while bracket member 73 is mounted on stud 59. Each of the bracket members are inclined in the direction of the respective supporting pedestals and each carry contact members 74 and 75 respectively. These contact members are aligned with the disc-like contacts 56 and 57 carried by the end of cross arm 53. That is, in one position of the switch as illustrated for example in Figs. 1 and 2, disc-like contact 57 establishes connection with stationary contact 75 with the reciprocating core member 29 in its extreme ejected position projecting from the solenoid casing, whereas in the opposite remote position, indicated in dotted lines in Fig. 2, where reciprocating core member 29 is moved to the extreme position within the solenoid, disc-like contact 56 establishes connection with stationary contact 74. Studs 58 and 59 carry an assembly of washers, nuts and terminals so shaped and streamlined as to minimize brush or corona loss under conditions of high potential.

For example, stud 58 has washer 76 thereon with nuts 77 and 78 screw threaded thereon, with intermediate washer 79 and end washer 80 thereon, and completed by a ball terminal 81 for preventing, insofar as practicable, losses of corona or brush discharge under high tension conditions. Stud 59 includes washer 82 thereon with nut 83 screw threaded thereon, followed by washer 84 and streamlined capping nut 85. These parts are shaped to minimize brush or corona discharge. Similarly the studs 60 and 61, extending from pedestal insulators 3 and 4 serve as supporting means for contact assemblies which are mounted on brackets 86 and 87. Bracket 86 supports contact 88 included in a plane which extends at an obtuse angle with respect to the base plane and serves to establish connection with the disc-like contact 54 when cross arm 53 is moved to the dotted line position illustrated in Fig. 2. Bracket 87 carries contact 89 inclined at an obtuse angle with respect to the base plane of the switch for establishing contact with the disc-like contact 55 when cross arm 53 is moved to the position shown in full line in Figs. 1 and 2 with reciprocating core member 29 ejected from the solenoid support 2. The stud 60 is protected against loss due to brush and corona discharge in a manner similar to the arrangement illustrated for stud 59 in Fig. 2, that is, cap nut 90 shaped to minimize loss by

brush or corona discharge is secured over nut 91 engaged on stud 60 providing for an electrical connection thereon while maintaining a substantially streamlined terminal.

5 Thus it will be seen that the switch arm is shiftable through the distance of an acute angle for transferring connections from one circuit to another. The switch has application to a variety of high potential circuits.

10 The pedestal insulators 6, 5, 3 and 4 may be formed from various materials of highly insulating qualities. I have used various forms of vitreous insulators and realize that porcelain and many of the synthetic insulation materials now

15 available are admirably suited for insuring high frequency insulation of the switch of my invention. Accordingly I intend that the pedestal insulators disclosed herein may be formed from any suitable insulation material without limitation.

20 Although I have described my invention in one of its preferred embodiments, I desire that it be understood that modifications may be made and that no limitations upon my invention are intended other than may be imposed by the scope of the appended claims.

What I claim as new and desire to secure by Letters Patent of the United States, is as follows:

1. A pedestal insulator supportable from a metallic base, comprising a pedestal structure 30 formed from insulation material, said pedestal structure having screw-threaded recesses symmetrically arranged in each end thereof; electrically conducting graphite packed in each of said recesses, metallic members screw-threaded into each of said recesses and abutting the graphite packed therein, the screw threaded member in one end of said pedestal insulator serving to secure said insulator with respect to a supporting base and the screw-threaded member in the opposite end of said pedestal insulator serving as mounting means for an electrical contact on the end of said insulator, said graphite packed in each of said recesses forming an electrically conductive column internally of said pedestal structure corresponding in transverse section to the section of said screw-threaded metallic members.

2. A pedestal insulator supportable from a metallic base, comprising a tapered member of insulation material having screw threaded axially aligned recesses in opposite ends thereof, a packing of electrically conducting graphite disposed in each of said screw-threaded recesses, a screw 55 member passing through said metallic base and entering the screw-threaded recess in one end of said insulator and abutting the electrically conducting graphite in said recess for compressing the graphite therein, a screw threaded member 60 engaging the screw-threaded recess in the opposite end of said insulation member and abutting against the electrically conducting graphite therein for compressing the graphite, and an electrical terminal secured in position by said 65 last mentioned screw threaded member, said packing of graphite forming an electrical conductive column internally of said tapered member adjacent each end thereof, corresponding in section to the section of said screw threaded members.

3. A pedestal insulator supportable from a metallic base, comprising a tapered member of insulation material having axially aligned screw-threaded recesses in opposite ends thereof, a 75 packing of conductive composition disposed in

each of said screw-threaded recesses, a screw member passing through a supporting metallic base and entering the screw-threaded recess in one end of said insulator and abutting the conductive composition in said recess for compressing the conductive composition therein, a screw-threaded member engaging the screw-threaded recess in the opposite end of said insulation member and abutting against the conductive composition therein for compressing the conductive composition, whereby, a compacted conductive path is provided between said screw members and the insulation material of the pedestal insulator along a central axis therethrough and, a contact device secured in position by said last mentioned screw threaded member said packing of conductive composition internally of said tapered member of insulation material corresponding in transverse section to the transverse section of the screw-threaded members.

4. A pedestal mounted contact structure comprising a supporting base, a substantially solid member formed from insulation material, said substantially solid member being axially recessed in opposite ends thereof where the recesses terminate remote from the solid central section of said member, said recesses being internally screw threaded and forming pockets at the ends thereof interiorly of said member, a packing of electrically conducting composition material forming a filling for the pockets in said recesses and screw members extending into the opposite ends of said member and establishing electrical and mechanical contact with the filling of electrically conducting composition therein, one of

said screw members operating to connect said insulation member to said base and the other of said screw members operating to support an electrical contact device, the electrically conducting composition material forming columns internally of said solid insulator substantially equal to the transverse section of said screw members.
